UNITED STATES PATENT OFFICE.

HARRY J. SCHWEHM AND ERNEST SCHWEHM, OF PHILADELPHIA, PENNSYLVANIA.

HORSEHAIR-CLOTH.

1,183,406.

Specification of Letters Patent.

Patented May 16, 1916.

Application filed April 30, 1915. Serial No. 24,892.

To all whom it may concern:

Be it known that we, HARRY J. SCHWEHM and ERNEST SCHWEHM, citizens of the United States, residing in the city of Philadelphia, State of Pennsylvania, have jointly invented certain new and useful Improvements in Horsehair-Cloth, of which the following is a full, clear, and exact description, reference being had to the accompanying drawings, forming a part of this specification.

Our invention relates to improvements in horse-hair cloth used for stiffening purposes in garments and for other purposes and comprising horse-hair weft threads interwoven with warp threads of suitable material.

This cloth has been objectionable for the reason that horse-hair weft threads of the cloth when in use, frequently shift their positions relatively to the warp threads and often work their way out of the fabric, resulting in many obvious annoyances and in much discomfort to persons wearing garments having the horse-hair cloth therein.

The object of our invention is to overcome this objection to a greater extent than heretofore and to produce a horse-hair cloth in which the warp threads may be woven in close relation to each other and in which the warp threads are interwoven with the horse-hair weft threads in a novel manner which results in increasing the binding action of the entire mass of warp threads on the weft threads.

With this object in view, our invented fabric consists of the novel combinations and arrangements of the threads thereof, as will be hereinafter fully described and particularly claimed.

In the accompanying drawings, illustrating our invention, Figure 1 is a plan view of a horse-hair cloth embodying my invention. Fig. 2 is a section thereof, in the direction of the weft threads, on line 2-2 of Fig. 1. Fig. 3 is a section thereof, in the direction of the warp threads, on line 3-3 of Fig. 1.

Referring to the drawings, 4 designates the horse-hair weft threads and 5 the warp threads which may be composed of any suitable material.

The warp threads 5 are arranged in two sets of pairs 6 and 7, the pairs being located side by side throughout the width of the fabric. The pairs 6 of one set alternate

with the pairs 7 of the other set, and each thread of each pair of each set passes over and under the weft threads 4 in alternate succession. The threads of each pair 6 are located on the same side of each other throughout the length of the fabric, and they cross each other between each two adjacent weft threads. The threads of each pair 7 are located first on one side and then on the other side of each other in alternate succession, crossing each other laterally and being twisted first in one direction and then in the reverse direction and being held in twisted condition by the horse-hair weft threads 4 extending through the twisted portions of the threads 7. The warp threads 5 of the pairs 6 and 7 of both sets thereof are passed over and under the weft threads 4 and arranged relatively to each other so that the several warp threads 5 pass over and under the same weft thread 4 in alternate succession: That is to say, where one warp thread 5 of either pair 6 or 7 passes over a weft thread 4 the companion thread of the warp thread thus passing over the weft thread and the nearest next adjacent warp thread of the other pair will pass under the weft thread; and where one warp thread 5 of either pair 6 or 7 passes under a weft thread 4 the companion thread of the warp thread thus passing under the weft thread and the nearest next adjacent warp thread of the other pair will pass over the weft thread.

By the novel construction hereinbefore described, the warp threads 5 of each pair 6 and 7 exert pressure upon the top and against the bottom of the weft threads and the pressure of the threads of the pairs 6 which are not twisted is less than the pressure of the threads of the twisted pairs of threads 7 due to the difference in the manner of weaving, the threads 6 having only a longitudinal pulling action against the weft threads 4 and the threads 7 having a tendency to untwist in addition to their longitudinal pulling action; and, as the horse-hair weft threads 4 are engaged on the top thereof by one thread of one of the pairs 6 and by one thread of one of the other pairs 7 immediately on the respective sides of each warp thread 5 which engages the bottom of the same weft thread, and the converse where a weft thread 4 is engaged at the top thereof by a warp thread 5, it follows that the combined action of the two

sets of pairs of warp threads 6 and 7 tends to and does produce irregular waves in the weft threads and thus effectually preventing the smooth horse-hair weft threads from shifting their positions in the fabric when it is in use.

We claim:

1. A woven fabric comprising horse hair weft threads and two sets of pairs of warp threads, in alternating relation, the component threads of each pair of one set alternating in passing over and under adjacent weft threads and crossing the horizontal plane of each other between adjacent weft threads, and the threads of each pair of the other set passing respectively over and under each of the weft threads and also crossing each other laterally to form a twist between adjacent weft threads.
2. A woven fabric comprising horse hair weft threads and two sets of differently interwoven pairs of warp threads in alternating relation, the component threads of each pair of one set alternating in passing over and under adjacent weft threads and crossing the horizontal plane of each other between adjacent weft threads, and the threads of each pair of the other set passing respectively over and under each of the weft threads and also crossing each other laterally to form a twist between adjacent weft threads.

ing succession as to pairs of the several sets, the component threads of each pair of one set passing alternately over and under adjacent weft threads without crossing each other laterally, and the component threads of the adjacent pair in the other set passing respectively over and under each of the weft threads and also crossing each other laterally to form a twist between adjacent weft threads, whereby the binding effect of the alternating pairs of warps differs in pressure on the weft threads successively throughout the fabric.

In testimony whereof, we have hereunto affixed our signatures this 12th day of April, A. D. 1915.

HARRY J. SCHWEHM.
ERNEST SCHWEHM.
